CHARLES S. ASH, OF BIRMINGHAM, MICHIGAN

ADJUSTABLE GUNSTOCK

Application filed May 7, 1931. Serial No. 535,640.

This invention relates to fire arms wherein the gun stock is made adjustable relative to the breech, and its object is to provide a construction whereby adjustment of the stock 5 may effect a drop of the stock heel, a drop of the comb, or a change in the effective length of the stock to give a perfect fit of the same to the shoulder of the user and relative positioning of the parts to suit that particular individual. A further object is to provide a very simple and rigid construction which is such that adjustment may be quickly and accurately made, or the gun stock quickly detached, thereby eliminating the take-down 15 feature and its complication, common to this class of guns.

It is also an object of the present invention, to provide a metal stock or grip which is light in weight, very strong and rigid, is cheap to manufacture, and is particularly adapted to be provided with decorative and other external features.

With the above and other ends in view, the invention consists in the matters hereinafter set forth, and more particularly pointed out in the appended claims, reference being had to the accompanying drawings in which—

Figure 1 is a side elevation of a gun illustrative of an embodiment of the present invention;

Fig. 2 is a plan view of the same;

Fig. 3 is a sectional detail, substantially upon the line 3—3 of Fig. 1;

Fig. 4 is a side elevation, showing a modified construction;

Fig. 5 is a sectional detail substantially upon the line 5—5 of Fig. 4;

Fig. 6 is a side elevation, partly in section, showing a further modified construction;

Fig. 7 is a section substantially upon the line 7—7 of Fig. 6;

Fig. 8 is a detail showing a further modified construction in side elevation; and

Fig. 9 is a section upon the line 9—9 of Fig. 8.

As shown in Figures 1 and 2, 1 indicates the usual barrel or barrels of the gun which are pivotally connected as at 2 in the usual manner, to the lock chamber 3 having the 50 usual locking lever 4 for locking the barrel or

barrels in extended position and adapted to enclose firing pins (not shown) adapted to be operated by the triggers 5 projecting from the lower side of said chamber. Formed integral with the rear end of said chamber 3 as 55 a continuation thereof, is a downwardly curved grip stock or hand grip 6, the lower end portion of said grip, as shown in Fig. 1, being curved concentrically about a point *a* located in a vertical plane indicated by the 60 line *b* shown in Fig. 1, passing vertically through the area contiguous to one of the triggers 5, said point being substantially in the horizontal plane (indicated at *c*) of the lower end of said grip. This curved end portion of said grip, may, as shown, be cylindrical in cross-section and formed with a slot 7 extending therethrough to receive a tongue 8 formed integral with a plate 9 secured to the forward end of a gun stock 10. This 70 plate 9 is curved in the direction of its length to correspond with the curvature of said grip 6, and said tongue is formed with an elongated transverse opening or slot 11 through which a screw bolt 12 extends, said 75 bolt having a head 13 at one end to engage one side of the stock 6, and screw-threaded at its opposite end to screw into a screw-threaded opening in the opposite side of the stock. The stock 10 may, therefore, be swung about 80 the point *a* by loosening the bolt 12 and moving its tongue 8 longitudinally of the slot 7 in the curved grip 6, and by tightening said bolt, said stock will be rigidly secured to said grip in adjusted position.

By this adjustment of the stock 10 upon the curved end of the grip, the position of the stock relative to the barrel 1 may be changed to suit the user of the gun, and the over-all length of the stock and grip is also changed 85 by sliding the stock upwardly along the curved grip during such adjustment. This adjustment also raises or lowers the heel or shoulder end 14 of the stock relative to the line of sight along the barrel as indicated at *d*, and at the same time, raises or lowers the comb 15 of the stock relative to said line, maintaining the proper relative position of these parts and to said line, due to the position of the point *a* about which the stock 90 95 100

swings, and which point does not change but remains in the vertical plane *b* below the triggers, the grip thus remaining unchanged and unaffected by the adjustment of the stock.

5 As shown in Fig. 4, adjustment of the stock 10 may also be secured by securing to the forward end of said stock, a connecting member 16 having a forward side face 17 which is inclined to the vertical, in the direction of its length and is curved in cross-section to conform to the curvature of the cylindrical lower end portion 18 of the grip 6, this end portion 18 having a rear side which is straight and is inclined to the vertical, in the direction of its length upwardly toward the end of the barrel 1. This connecting member 16 is rigidly secured to the forward end of the stock, by being formed with side flanges 19 to overlap the end of said stock at the sides thereof and with lugs 20 provided with openings to receive screws 21. This connecting member 16 is formed with an elongated opening 22 through which passes a bolt 23, said bolt also passing through an opening in the end portion 18 of said grip, with a nut 24 on its screw-threaded inner end within a recess in the end of the stock, which recess is closed by the securing of the connecting member 16 to the end of the stock.

35 By loosening the bolt 23, the stock 10 with its connecting member 16 may be slid up or down longitudinally of said end portion 18, thus adjusting the stock toward or from the line of sight without changing the relative positions of the shoulder end 14 and comb 15, and at the same time lengthening or shortening the distance from said end 14 to the rear end of the barrel, due to the upward and forward inclination of said end 18 and member 16 forming the abutting end of the stock.

40 As illustrated in Figs. 6 and 7, the gun stock 25 may be formed hollow, with an integral end wall 26 which is inclined upwardly and forwardly, the same as the connecting or end member 16 of the construction shown in Fig. 4, and the opposite end of this stock is closed by a plate 27, curved to properly set against the user's shoulder and secured to the end of the hollow stock in any suitable manner. This stock is detachably and adjustably secured to the grip portion 18 in the same manner as shown in Fig. 4, that is, by the bolt 23 passing through the grip and 45 through the elongated opening 22 in the wall 26, with the nut 24 on the inner end of said bolt.

45 By making the stock 25 hollow, the construction is cheapened in cost and lightened in weight without sacrificing strength or rigidity, and the cost and weight of the gun may be further reduced by also forming the hand grip 28 hollow, as shown in Figs. 8 and 9, it being given the desired external shape and formed to provide the proper end wall

29 to abut the end wall 26 of the stock 25. In the construction shown in Figs. 8 and 9, this end wall of the grip 28 is roughened or corrugated and the end wall 26 of the stock is correspondingly corrugated to give an interlocking engagement when the parts are secured together by the bolt 23 and provide a rigid connection. In this construction the walls 26 and 29 are flat instead of being transversely curved, and, therefore the stock has a longitudinal adjustment only, upon the grip.

50 For decorative purposes and to provide a firm grip for the user's hand and fingers upon the stock 25 shown in Fig. 6 or upon the grip 28 of Fig. 8, the opposite sides of the stock 55 may be provided with a roughened area or panel 30, and to provide such an area where the stock 25 is formed with thin side walls, a slight depression 31 of the desired shape and size of this area, is formed in each side of the stock and a piece of roughened or otherwise 60 decoratively formed rubber 32 or other suitable composition, is laid into each of these depressions and cemented or otherwise secured in place therein. The stock 25 or grip 65 28 or other part of the gun which is formed of thin metal, may thus be provided with areas of any desired shape and size to give a 70 better hold on the gun and to increase its attractive appearance, and such areas may be 75 very cheaply applied without materially adding 80 to the weight or cost of the gun.

85 In Figure 1 the adjustment of the stock 10 is secured through a swinging movement, up and down, upon the grip 6, but no lateral movement of the stock relative to the grip is provided for. In the construction illustrated in Figs. 8 and 9, no lateral adjustment of the stock is secured, said stock being movable up or down along the end wall of the grip only.

90 In Figures 4, 5, 6 and 7 the constructions are such that the stock 10 or 25 may be swung laterally as illustrated in dotted lines in Figure 7, upon the end portion of the grip 18 which is cylindrical in cross-section, the slot 110 22 in the end wall of the stock being of sufficient width to permit lateral swinging movement of the stock, and the nut 24 where it seats upon said wall, being curved to conform to the curvature of said wall and the 115 axis of such swinging movement. With this arrangement, the stock may be swung a limited degree, laterally out of alignment with the gun barrel to fit the shoulder of the particular user and properly position the barrel 120 relative to his line of sight along the barrel.

125 Obviously other changes in the construction and arrangement of parts, may be made within the scope of the appended claims, without departing from the spirit of the invention, and I do not, therefore, limit myself to the particular construction shown.

Having thus fully described my invention, what I claim is:—

130 1. In a gun having a barrel and a lock

chamber to which said barrel is connected at its rear end, a grip stock integral with said lock chamber, a stock adjustably engaged with the rear end portion of said grip stock, said rear end portion of said grip stock and the forward end of said stock being transversely curved to permit swinging adjustment of said stock upon said grip stock laterally of the line of sight along said barrel, and means for securing said stock to said grip stock in the position to which it is adjusted.

2. A gun having a barrel and a lock chamber to which said barrel is connected adjacent its rear end, a hollow metal grip stock formed with thin side walls having depressions in opposite sides thereof and extending rearwardly from said lock chamber and formed with an end wall, a stock formed hollow throughout its length with thin side walls and having a forward end to engage said end wall of said grip stock, means for adjustably securing said stock to said end wall of said grip stock, and composition strips in said depressions in the sides of said hollow grip stock.

3. A gun having a barrel and a lock chamber to which said barrel is connected adjacent its rear end, a grip stock extending rearwardly from said lock chamber and formed with an end wall, a stock formed hollow throughout its length with thin side walls and with a forward end wall to abut said end wall of said grip stock, and means for securing said stock to said grip stock with said end walls in contact.

4. A gun having a barrel and a lock chamber to which said barrel is connected at its rear end, a grip stock extending rearwardly from said lock chamber and having a portion curved transversely, a stock having a forward end surface curved transversely to engage and conform to the curvature of said grip stock portion, and means for securing said stock to said grip stock and permitting lateral swinging adjustment of said stock upon said grip stock.

5. A gun having a barrel and a lock chamber to which said barrel is connected at its rear end, a grip stock extending rearwardly from said lock chamber and formed with a side extending upwardly and forwardly from the lower end thereof and curved transversely, a stock having a forward end to engage said side of said grip stock, and means permitting lateral swinging adjustment of said stock upon said grip stock and for securing said stock in adjusted position upon said grip stock.

6. A gun comprising a barrel, a lock chamber to which said barrel is connected at its rear end, a grip stock extending rearwardly from said lock chamber, and a stock secured to said grip stock and formed hollow with thin walls, the side walls of said stock being formed with depressions of panel form and

the front end wall of said stock being formed to exteriorly conform to the end portion of said grip stock and secured thereto, and a sheet of suitable material secured within each of said depressions to provide paneled sides for said stock.

In testimony whereof I affix my signature.

CHARLES S. ASH.
